(57) **CLAIM**

The ornamental design for an item of jewelry, as shown and described.

DESCRIPTION

FIG. 1 is a front view of an item of jewelry, showing my new design,

FIG. 2 is a rear view thereof;

FIG. 3 is a front and bottom perspective view thereof;

FIG. 4 is a rear and top perspective view thereof.

FIG. 5 is a front view thereof, with a portion of the charms flipped over for ease of illustration; and,

FIG. 6 is a rear view thereof, with a portion of the charms flipped over for ease of illustration.

The portion of the chain covered by a translucent overlay forms no part of the claimed design.

1 Claim, 6 Drawing Sheets
